D526,079 S * 8/2006 Heun D26/60
7,097,321 B2 * 8/2006 Mehler et al. 362/190

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view illustrating the instant invention positioned around the ear of an individual.

The portions of figures illustrated in broken lines are for environmental purposes only and form no part of the claimed design.
